UNITED STATES PATENT OFFICE.

JOHN G. GIBSON, JR., OF ATLANTIC CITY, NEW JERSEY.

GRATE STRUCTURE.

Application filed August 17, 1921. Serial No. 492,940.

To all whom it may concern:

Be it known that I, JOHN G. GIBSON, Jr., a citizen of the United States, residing at Atlantic City, in the county of Atlantic and State of New Jersey, have invented certain new and useful Improvements in Grate Structures, of which the following is a specification.

One object of my present invention is to provide an improved grate structure which can be used with advantage in connection with furnaces, boilers and heaters and which will be so constructed that it will supply air in an improved and novel manner capable of effecting a practically complete combustion of the fuel.

Another object is to include in my invention an improved air cooled distributor capable of supplying a desired amount of oxygen to effect the combustion.

Another object is to so construct my improved structure that the grate bar body can be supplied with water so as to keep said body comparatively cool and prevent the same from readily burning out.

A further object is to so construct my improved structure that it can be manufactured and installed at a low cost and will be durable.

These objects, and other advantageous ends which will be described hereinafter, I attain in the following manner, reference being had to the accompanying drawings in which

Figure 1 is a top plan view of a grate structure embodying my invention.

Figure 2 is an enlarged section of said structure taken on the line 2—2 of Figure 1.

Figure 3 is a top plan view of one of the air cooled distributing members which is made in accordance with my invention.

Figure 4 is an inverted plan view of said member.

Figure 5 is an end elevation of said member.

Figure 6 is a sectional view of said member taken on the line 6—6 of Figure 3.

Figure 7 is a side elevation of said member.

Figure 8 is a section of said member taken on the line 8—8 of Figure 3.

Figure 9 is a top plan view showing the body of the grate cast in one piece and differing from the form of the grate body

illustrated in Figure 1 in which the bar portions of the body are separate pieces.

Figure 10 is a section taken on the line 10—10 of Figure 9.

Figure 11 is a front elevation illustrating the body of the grate cast integral with a sectional boiler.

Figure 12 is a section taken on the line 12—12 of Figure 11, and

Figure 13 is an enlarged fragmentary section taken on the line 13—13 of Figure 1.

Referring to the drawings and particularly to Figures 1 to 8 inclusive, 13 represents the body of a grate which includes hollow supports 14 provided with openings 15 for attachment of pipes for admission of water for cooling purposes. The supports are arranged side by side, are preferably T-shaped at their ends, as indicated at 16, and are placed with their T-shaped ends abutting each other as shown in Figure 1.

In transverse section as shown in Figure 2 the supports 14 are of less width at their tops 18 than at their bottoms 19 and ledges 20 or shoulders 20 are produced between the tops 18 and bottoms 19; said ledges extending outwardly from the side surfaces 21 of the top parts of the supports to the side surfaces 22 which are below the top parts 21.

By constructing the grate body portion 13 as above described, a space 23 is provided between the opposed side surfaces 22 of adjacent supports 14; said space extending between the inner surfaces 24 of the extensions. These spaces 23 are open at their top and bottom and it is within these spaces that I insert my improved air cooled distributing bars 25 which are preferably made of cast metal. Each of the bars 25 as clearly shown in detail in Figures 3 to 8 inclusive has a top plate portion 26 which is elongated horizontally and from which depends two longitudinal flanges having their ends joined so as to form a continuous skirt flange 27. The top plate portion 26 extends laterally beyond the outside of the skirt flange 27 to provide a lateral flange 28 which is preferably in the same plane as the remaining part of the top plate portion 26.

Immediately below the lateral flange 28 is a shoulder 29, the outer surface 30 of which is located inwardly from the outer edge surface 31 of the lateral flange 28. The shoul-

der 29 has recesses 32 at distances apart which lead upwardly from the under surface 33 as clearly shown in Figure 7. The lateral flange 28 has notches or cut-out portions 34 at distances apart leading inwardly from the outer surface 31.

The plate portion 26 has rows of upright perforations 35 which lead outwardly from the chamber 36 formed by the skirt flange 27 and inclined perforations 37 lead outwardly from the chamber 36 as clearly shown in Figures 2 and 6.

I preferably construct the parts so that the distance between the bottom surface 33 of the shoulder 29 and the top surface of the plate portion 26 is substantially equal to the distance between the ledge 20 and the top surface of the grate body 13 so that the plate portion 26 will fit flush within the space between the side surfaces 21 of the top of the adjacent supports and between the surfaces 24 of the ends of the supports as clearly shown in Figures 1 and 2.

The skirt flange 27 is of less width and length than the space 23 and when the distributing bars 25 are placed in position there will be a space between the outer side and end surfaces of each skirt flange and the grate body; such space being shown at α in Figures 2 and 13.

With the construction above described, when the bars are placed in position the shoulders will rest on the ledges 20 and the recesses 32 will be in communication with the space α surrounding each skirt flange and the recesses will also be in communication with the channel space indicated at y between the surfaces 30 and the side surfaces 21 of the supports 14 which are immediately below the lateral flange 28, and since the notches extend from the top to the bottom of said lateral flanges, these notches will be in communication with the channel space y between the distributing members and the grate body. It will be noted further that the channel space y entirely surrounds the shoulder and thus air can pass upward through the space α , then through the recesses 32 into the channel y and then upwardly through the notches to the fuel. Air can also pass upwardly through the chamber 36 and through the perforations 35 and 37; the air which passes through the perforations 35 being directed in an approximately vertical direction while the air which passes through the perforations 37 will be deflected at a slant over the tops of the supports 14. Thus the fuel above the grate can be supplied with an abundance of oxygen and the distributing bars will be kept comparatively cool due to the fact that they are practically surrounded by air space, and any heat imparted to the distributing bars and to the grate body will be taken up by the air so that the air when delivered into the fuel

will be heated and more readily combustible together with the fuel.

With my construction as above described the distributing bars can be readily put in position since there is no chance for any binding action and the bars can be cast in a single piece. At the same time they are capable of distributing the air over a widely extended zone.

In Figures 9 and 10, I have shown a grate body 13^a which is similar to the grate body 13 above described with the exception that the supports 14^a are all cast in one piece. In all other respects the construction is similar to that above described in connection with the grate body 13 and I have given similar parts corresponding reference characters with the exponent "a".

In Figures 11 and 12, I have shown the supports 14^c cast integral with the sections 38 of a boiler 39 and my improved distributing bars can be positioned between the supports 14^c in the same manner as above described in connection with Figures 1 to 8 inclusive. The similar parts are given corresponding reference characters with the exponent "c".

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A grate structure including supports spaced from each other in a portion of their length and provided with ledges; a top plate positioned upon the ledges between the supports and provided with air passages, and a continuous skirt flange depending between the supports and spaced therefrom to form air passages.

2. A grate structure comprising supports provided with ledges; a top plate having vertical and inclined air passages; a lateral flange extending from the top plate and provided with air passages; a skirt flange depending from the top plate and spaced from the supports to form air passages, and a shoulder on the skirt flange resting on the ledges and having recesses forming air passages.

3. A grate structure comprising supports provided with ledges; a top plate having vertical and inclined air passages; a lateral flange extending from the top plate and having notches forming air passages; a skirt flange depending from the top plate and spaced from the supports to form air passages, and a shoulder on the skirt flange rest-

ing on the ledges and having recesses forming air passages.

4. A grate structure including supports spaced from each other and provided with ledges and a top plate positioned between the supports having a perforated center and notched edges forming air passages, and shoulders resting on the ledges with air passages between it and the ledges and an air passage, between the shoulder and the support, communicating with the last mentioned air passages and the notches.

5. A grate structure including supports spaced from each other in a portion of their length and provided with ledges; a top plate positioned between the supports, having a perforated center and notched edges to form air passages, and shoulders resting on the ledges and having recesses forming air passages, the shoulder being positioned to form

an air passage communicating with the recesses and the notches, and a flange depending from the top plate between the supports to form an air passage leading to the recesses and an air passage to the perforations. 25

6. A grate structure including hollow supports having T-shaped ends abutting each other and provided with ledges; a top plate positioned upon the ledges between the supports and provided with air passages, and a continuous skirt flange depending from the plate between the supports to form air passages. 30

In testimony whereof I have signed my name to this specification in the presence of 35 two subscribing witnesses.
